[57] **CLAIM**

The ornamental design for a credenza, as shown and described.

DESCRIPTION

FIG. 1 is a perspective view of a credenza showing my new design.

FIG. 2 is a top plan view thereof.

FIG. 3 is a bottom plan view thereof.

FIG. 4 is a side elevational view, the opposite side being identical thereto.

FIG. 5 is a front elevational view, the rear view being identical thereto.

FIG. 6 is a perspective view of a modified form of the credenza of FIG. 1.

FIG. 7 is a top plan view thereof.

FIG. 8 is a bottom plan view thereof.

FIG. 9 is a side elevational view, the opposite side being identical thereto; and,

FIG. 10 is a front elevational view, the rear being identical thereto.

The broken lines in the drawings are for illustrative purposes only and do not form part of the claimed design.
